UNITED STATES PATENT OFFICE.

BERNHARD MONTGOMERY BESKOW, OF NEW YORK, N. Y., ASSIGNOR OF ONE-FOURTH
TO CHARLES S. CHAMPION, OF BROOKLYN, NEW YORK.

AIRSHIP.

1,031,904.

Specification of Letters Patent. Patented July 9, 1912.

Application filed March 16, 1909. Serial No. 483,795.

To all whom it may concern:

Be it known that I, BERNHARD MONTGOMERY BESKOW, a citizen of the United States, and a resident of New York, in the county 5 of New York, and State of New York, have invented certain new and useful Improvements in Airships, of which the following is a specification.

This invention relates to air ships, and 10 especially to that type known as aeroplanes, the principal object of the invention being to provide means for automatically maintaining the equilibrium of the machine both transversely and fore and aft when the 15 planes thereof are acted upon by strong transverse or fore and aft air currents tending to destroy that equilibrium. This feature of the invention is directed chiefly to the maintenance of equilibrium in the direction of the transverse axis of the aeroplane but also includes the maintenance of equilibrium in the direction of the longitudinal 20 axis of the machine.

In connection with the means employed 25 by me for automatically maintaining the equilibrium of the aeroplane I also prefer to employ means for automatically preventing such action except at such times as the air pressure tending to disturb the equilibrium 30 of the machine rises above a certain predetermined point. The equilibrium of an aeroplane of good construction, such for example as one of the Wright type, is not seriously affected by ordinary gusts of wind 35 striking the planes of the machine from either side or from either end of the machine. It is only when the wind blows with considerable force from one of these points that it is necessary to bring into operation 40 means for automatically counteracting the tendency of such air current to disturb the equilibrium of the aeroplane. Until the air pressure reaches and passes a certain predetermined point, readily determined in practice and dependent upon the weight of the 45 machine, the area of the planes, etc., it is unnecessary to bring into action any automatic means for maintaining equilibrium. For this reason I make use of means for resisting the tendency of any air currents, except those exerting excessive pressure, to 50 operate the means for automatically maintaining the equilibrium of the machine. In

the preferred construction I employ one or more controlling planes so located as to receive the thrust of the air current and cause an automatic adjustment of one or more planes on the machine, preferably in a manner analogous to the manual adjustment of the side planes heretofore employed for 55 maintaining manual control of the equilibrium of the machine. In conjunction with such controlling plane or planes I may make use of a spring of suitable tension, adjustable within proper limits, for preventing any relative movement of said controlling plane or planes unless the wind pressure rises above a predetermined point, thus preventing the automatic action for maintaining equilibrium until the wind pressure 65 rises above that which would dangerously affect such equilibrium. This auxiliary means is also an important feature of the present invention.

The framing of aeroplanes heretofore used has not combined in a thoroughly satisfactory manner the essential elements of lightness and strength, and an important feature of the present invention is the provision of an improved framework so braced 80 as to oppose greater resistance to the strains of the load borne by it and to the action of strong winds thereon than has been the case heretofore. In the framework employed by me the framing is braced laterally by a series of connected arches lying preferably in a common plane and so connected as to oppose great resistance to pressure from every point, these arches being preferably connected in such a manner that each is tangent to every other that lies in the same plane.

Other features of the invention relates to improved means for steering the machine and maintaining manual control of all its 95 movements, and to an improved type of propeller, propeller-frames, motor-frames, etc., by means of which greater rigidity of the principal operating parts and supporting framing is obtained than heretofore. 100 This and other features of the invention which will be hereinafter described and claimed are illustrated in the accompanying drawings, in which—

Figure 1 is a plan of a flying machine of 105 the aeroplane type illustrating one embodiment.

ment of the various features of my invention; Fig. 2 is a side elevation of the same; Fig. 3 is a rear elevation of the same; Fig. 4 is a perspective illustrating a modification 5 of the means for maintaining the equilibrium of the aeroplane in the direction of its longitudinal axis; and Figs. 5, 6 and 7 are details illustrating on an enlarged scale the manual controlling means preferably 10 employed for steering the machine, changing the positions of the side and end planes to maintain equilibrium, etc.

Similar characters designate like parts in all the figures of the drawings.

15 In most respects my improved aeroplane is or may be similar to aeroplanes that have been put into successful use. The essential features of the Wright type of machine, for example, may be employed, except as it may 20 be necessary to modify them to adapt the various features of my invention thereto. Thus, the framework, which is designated generally by 2, may be of the open box-like frame type employed in the Wright type of 25 aeroplane, the various members of the frame being constructed preferably of light metallic rods or tubes suitably connected by brazing or otherwise. On this main frame 2 will be mounted the motor (not shown) 30 and the propelling mechanism operated thereby. The propelling mechanism will usually include one or more rotary propellers, here shown as two in number, suitably mounted on the framework. In order to 35 balance the parts two are illustrated, one at each side of the motor frame and operator's station, these propellers being preferably mounted in annular frames suitably connected with the motor frame. The main 40 framework as a whole is illustrated herein as including three main frame pieces parallel with each other and disposed transversely of the machine. Each is made up of a plurality of arched pieces lying in a common plane and so connected as to give great 45 stiffness to the framework in the direction of its transverse axis. The three frame pieces just referred to are indicated at 3, 4 and 5 (see Fig. 1), the frame 4 being the central one and somewhat shorter than the other two, it being practically identical in construction with corresponding portions of the frame members 3 and 5. Each of these frame members 3, 4 and 5 consists in this 55 case of four main arched frame-pieces, designated respectively by 6, 7, 8 and 9. The frame-pieces 6, 7 and 8 are all illustrated as circular frames, the frame-piece 6 serving as a frame for the motor (not shown) and 60 the frame-pieces 7 and 8 serving as propeller frames, while the arched member 9 is a bowed rod or tube. All four of these parts 6, 7, 8 and 9 are preferably connected in such a manner that each is fastened to every 65 other, these connections being indicated at

10, 11, 12, 13 and 14, and each is tangent to every other at its point of contact therewith. The three frame-pieces 3, 4 and 5 made up in this manner are connected by suitable tie-rods or other members, such as 15, 16, 17 and 18 to form the open or skeleton box-like main frame 2. At opposite ends of this main frame 2, that is, at opposite sides of the aeroplane, may be connected adjustable frames, such as 19 and 20. Each of these is preferably of the same type of construction as the main frame, but the frames themselves are preferably pivoted to the main frame 2 and made up of horizontal and vertical parts pivotally connected to one another, this construction permitting the upper and lower sides of the box-like side-frames 19 and 20 to move always in parallelism as they are raised or lowered. The pivot points at which the side-frames 19 and 20 are connected to the main frame 2 are indicated at 21, 22, 23 and 24, and the remaining pivot-points of the horizontal and vertical elements of said side-frames are indicated at 25, 26, 27, 28, 29, 30, 31 and 32. 90 These side-frames may carry suitable means, in the construction illustrated, for maintaining the equilibrium of the aeroplane crosswise thereof and may be controlled by suitable means for tilting them up or down. 95 When one is tilted up the other should always be tilted down, and the side-frames are preferably so connected as to produce this result. Strong flexible connections, such as 33, are illustrated as extending from the lowermost outer points of the side-frames 19 and 20 over suitable guides, such as the rolls 34 and 35 located at the pivot-points 21 and 23, for maintaining this relation between the movements of the side frames. 100

The means for controlling either manually or automatically the equilibrium of the machine crosswise thereof embodies one or more planes shiftable to different angular positions with respect to side currents or gusts of air. Preferably the side frames 19 and 20 will carry the usual side planes (shown in Fig. 4) and also an additional controlling plane or planes disposed at a considerable angle to the regular side plane 1 or planes. Here two such controlling planes are illustrated, one of which is carried at one side of the main frame and the other at the opposite side of said frame, these controlling planes being designated by 36 and 37 respectively. They may be of any suitable construction and may be shiftable in any proper manner to different angular positions by wind pressure from one side or the other of the machine. They are preferably pivoted at the points 21 and 23 and are pendent therefrom at substantially a right angle to the side planes and to the transverse currents of air which are directed against one side of the machine. Being thus di- 1

rectly exposed to side wind pressure, they are readily shifted by such pressure, and their movements may be transmitted to the side planes for the purpose of automatically 5 obtaining an adjustment of the angular positions of the side planes which will correspond to the movements of the controlling planes. This movement will vary in accordance with the strength of the wind striking the controlling plane, and the side planes will be tilted more or less according as the controlling planes are shifted more or less by direct wind pressure. Thus the 10 angular adjustment of the side planes to maintain the equilibrium of the machine in the direction of the transverse axis thereof will correspond to the pressure exerted by the wind or current of air at the side of the machine. The connections from the controlling plane or planes 36 and 37 for obtaining this result may be any suitable for the purpose. They are here shown as connections such as 38 and 39 leading from the controlling planes directly to the side planes. 15 Similar connections are illustrated at 40, 41, 42 and 43 between the inner and outer, and upper and lower, portions of the side frames, these connectors running over rollers and being fastened at their ends only. It will 20 be clear that when either the controlling plane 36 or the controlling plane 37 is turned about its pivot by the pressure of the wind and forced inward at its lower end the side plane adjacent thereto and the side-frame on which it is mounted will be tilted downward, the opposite side-frame with its planes being tilted upward, that is, in the opposite direction, through substantially the same angle, this opposite adjustment of the side-frames 25 and planes tending to maintain the equilibrium of the machine crosswise thereof. This takes place by reason of the fact that the thrust of the wind on the upper side of the downwardly tilted side plane on the side of the machine nearest the wind tends to tip that side of the machine downward instead of upward, and the thrust of the wind in the same direction at the opposite side of the machine on the upper side of the upwardly 30 tilted side plane also tends to force said upwardly inclined side plane and the far side of the machine downward, thus preventing upward movement of the far side of the machine. In other words the wind striking the 35 upper side of the downwardly inclined plane at the near side of the machine spills over it and is caught by the upwardly inclined side plane of the far side of the machine and exerts its full pressure effectively 40 against the upper side or surface of said plane and thereby forces that side of the machine downward. The side planes being oppositely inclined, one downward and one upward, it is obvious that the pressure on 45 both is downward and no loss of lateral

equilibrium is permitted, for as soon as a downward pressure on one side of the machine is created, a corresponding downward pressure is called into play at the opposite side of the machine. Were both planes adjusted in the same direction, that is, both tilted upward or both tilted downward, the pressure of the wind in the former case would be exerted on the under surface of the near plane, and the upper surface of the far plane, while in the latter case, the wind pressure would be exerted on the upper surface of the near plane and the under surface of the far plane, and in either case would operate to turn the machine over. 50 However, by arranging the side planes oppositely in the manner described, any turning tendency of this kind that exists at any given moment is effectively neutralized. In a somewhat similar manner the equilibrium of the machine lengthwise thereof may be automatically preserved. For this purpose the front and rear controlling planes are preferably carried by the front and rear extensions of the main frame 2. The front extension of the main framework is designated generally by 44 and the rear extension by 45. On these front and rear frames are mounted adjustable controlling planes, such for example as the planes 46, 47 and 48 shown in Fig. 2. The plane 46 is pivoted at the extreme front end of the machine at 49, while the planes 47 and 48 are pivoted at 50 and 51 at intermediate points of the front and rear extension frames. In this case the plane 47 is functionally the ordinary front plane for varying the elevation of the machine, while the plane 46 is a controlling plane for automatically shifting the position of the front plane 47. The rear plane 48 is in this case a combined rear plane and controlling plane. It is operated by connections to the front planes and it controls the positions of said front planes when the wind pressure at the end of the machine is exerted at the rear of the same. The planes 46 and 47 are here connected, as by links 52, so as to move in unison to different angular positions. When a current of air strikes the under side of the front controlling plane 46 and tends to raise the front end of the machine the planes 46 and 47 are tilted upward, as shown for example in dotted lines in Fig. 2, and at the same time the rear plane 48 is tilted down through suitable connections, as for example to the position indicated in dotted lines, and the equilibrium of the machine in the direction of its longitudinal axis is thus automatically maintained. The connections between the front and rear controlling planes may be any suitable for the purpose, flexible connections, such as 53, passing over suitable guide-rolls, being illustrated herein for this purpose. 55 60 65 70 75 80 85 90 95 100 105 110 115 120 125 130

Both the side controlling planes and the end controlling planes may be held by suitable means from shifting their positions unless they are acted on by wind pressure in excess of that which would tend to disturb the equilibrium. The pressure which would do this depends upon the weight of the machine, the area of the planes, etc., and may be readily determined. For the purpose of preventing the automatic control of the equilibrium of the machine in any direction by the various controlling planes, strong springs may be employed to hold the controlling planes in their normal positions until they are acted on by excessive wind pressure, when the springs will yield and the planes move as before described. Such springs are illustrated herein in connection with the side controlling planes 36 and 37, and the front and rear controlling planes 46 and 48. The springs may be of any suitable type and their tension may be adjusted to permit them to resist wind pressure up to a predetermined point. Said springs are designated by 54, 55, 56 and 57. They constitute a simple and effective means for preventing unnecessary automatic shifting of the various parts of the mechanism used to control the equilibrium automatically, though not interfering in any way with any necessary automatic controlling action for maintaining equilibrium in the direction of either of the horizontal axes of the machine.

As before stated, two propellers are illustrated for the purpose of driving the machine. Each of these propellers in the construction shown comprises a hub with radiating propeller blades the ends of which are fastened rigidly to an inclosing rim. This construction gives great rigidity to the propeller and the efficiency of each propeller as a whole is correspondingly increased. These propellers are designated respectively by 58 and 59, and the rims thereof are indicated at 60 and 61. At their hubs they are illustrated as pivoted in bearings supported at the centers of spiders 62 and 63, the ends of the spiders being fastened to the circular propeller frames 7 and 8. The two propellers 58 and 59 are also shown as inclosed in conduits formed by steering-tubes shiftable to different positions to vary the direction of flight. These steering-tubes are indicated at 64, 65, 66 and 67, each being connected by a flexible or bellows-like connection with a propeller-casing, such as 68 and 69, to provide a continuous conduit at each propeller through which air may be sucked by the propeller and by which it may be driven. By changing the angular positions of these conduits, as indicated for example in Fig. 1, which shows them shifted from the normal straight-line positions, it will be clear that the machine as a

whole may be turned or steered in the direction corresponding to the turning of said steering-tubes. In order that these tubes may move together they are preferably directly connected, as by means of rods 70 and 71. The turning of these steering-tubes is manually controlled, preferably from a single central point, by suitable connections. Here a flexible connector is shown at 72 for this purpose, this connector extending from one of the tubes around a series of pulleys, such as 73, 74, 75, 76, 77 and 78 on the framework to the corresponding tube of the other propeller, the manual controlling means for shifting this connector and changing the position of the steering-tubes simultaneously being placed substantially at the center of the flexible connector.

In Fig. 4 I have illustrated a modification of the invention which illustrates more clearly than the other views the main elements of the machine, to wit, the planes, and which shows the angular positions to which the controlling planes, etc., may be shifted. It also illustrates a single controlling plane at the front and rear ends of the machine for automatically controlling the equilibrium in the direction of the longitudinal axis of the aeroplane. In other respects the construction in this view is or may be substantially identical with that hereinbefore described.

In both of the types of machines illustrated an inflated gas-bag may be used as an auxiliary to the planes of the machine for the purpose of preventing a too rapid descent of the machine in case any part becomes disabled and the control seriously affected. This gas-bag or balloon may be mounted substantially centrally and at its under side may follow the contour of the frame member 9, but is not illustrated herein, as it is only an auxiliary and the construction and use of such balloons are well understood.

In Figs. 5, 6 and 7 I have illustrated in detail the construction of one type of manual controlling means that may be employed to steer the machine to the right or to the left or ahead, as the case may be; and to tilt the front and rear planes to maintain its equilibrium longitudinally. Preferably a single controlling handle is used to perform all these functions, and its movements correspond substantially to the direction and nature of the controlling action desired. The object of this is to reduce as much as possible the strain on the operator and assure the prompt execution of any controlling function that may be required at any given time. In the construction illustrated a steering-post 79 is mounted on a suitable frame member 80 for turning movement and carries a segment 81 the movements of which are transmitted in any suitable manner to

the flexible connectors 72 by means of which the steering-tubes are operated. It will be clear that these tubes will be turned to the right or to the left as the handle 82 is turned 5 to the right or to the left, as said handle is secured to the upper end of the steering-rod 83, which though pivoted at 84 on the post 79 always turns with said post about its longitudinal axis. The tube 85 surrounds 10 the steering-post 79, and on it is fastened a locking segment 86 co-operative with a locking-pawl 87 slidable on the steering-rod 83. This pawl has a spring 88 interposed between it and the fixed stop 89 on the rod 83 15 and is normally held out of engagement with the teeth of the segment 86. The pawl, however, may be forced into locking engagement with the teeth of the segment in any angular position of the steering-rod or 20 lever 83 when said lever is turned about its pivot 84. This pawl is shown as operated by a locking and releasing handle 90 having suitable connections, such as the flexible conductor 91 and the lever 92 for operating the 25 pawl. The pawl 87 is guided on the rod 83 and also on a separate guide-rod 93 secured to the pivot of the lever 83. The combined steering-rod and lever 83 and segment 86 and the guide-rod 93 all move in unison 30 when the lever 83 is turned about its pivot 84. This movement may be transmitted, as through a flexible conductor 94, to any suitable mechanism, such for example as that for shifting the positions of the front and 35 rear controlling planes.

When the gas-bag or other means hereinbefore referred to is employed for checking the descent of the aeroplane, the air-ship as a whole may be considerably lighter than 40 air, that is, the gas-bag or other means for making the machine buoyant may be such as normally to cause the machine to ascend. In such cases I may employ means for increasing the weight of the air-ship after it 45 has ascended and making it considerably heavier than air, if desired. This means may be a load of any kind, of considerable weight, normally unsupported by the machine but connected therewith as by a cable, 50 which load may be picked up, as by a power-operated winch, after the machine has risen to a sufficient height to permit it to be propelled. This load may be carried at any suitable point on the framework after it has 55 been raised. It constitutes a supplemental load which permits ascension of an air-ship normally lighter than air, and converts it into an air-ship heavier than air after the machine has risen the proper distance.

60 What I claim is:

1. In an aeroplane, the combination with the main frame, of means operated by natural air currents and comprising controlling planes at the sides of the machine, for automatically maintaining the equilibrium of

the aeroplane in a crosswise direction, and means also operated by natural air currents and comprising controlling planes arranged fore and aft of the machine, to automatically maintain longitudinal equilibrium. 70

2. An aeroplane embodying side planes adjustable to different positions for maintaining the equilibrium of the aeroplane in one direction, and means comprising controlling planes at the sides of the machine, 75 for automatically adjusting the positions of both of said side planes.

3. An aeroplane embodying side planes adjustable to different positions for maintaining the equilibrium of the aeroplane in 80 one direction, and means comprising controlling planes at opposite sides of the machine for automatically adjusting said side planes in opposite directions.

4. An aeroplane embodying a pair of side 85 planes at opposite sides of the machine, and means, including controlling planes at opposite sides of the machine and disposed at considerable angles to said side planes and to side air currents for automatically shifting 90 the positions of said side planes to maintain the equilibrium of the aeroplane crosswise thereof.

5. In an aeroplane, the combination with the main frame thereof, of means operated 95 by natural air currents and including a hinged controlling plane at the side of the machine and disposed at a considerable angle to side air currents, for automatically maintaining the equilibrium of the aero- 100 plane crosswise thereof.

6. In an aeroplane, the combination with the main frame thereof, of means operated by natural air currents, and including an adjustable controlling plane at the side of 105 the machine, for automatically maintaining the equilibrium of the aeroplane in the direction of one of its horizontal axes, and means for preventing such automatic adjustment of said controlling plane by air 110 currents exerting less than a predetermined pressure.

7. In an aeroplane, the combination with the main frame thereof, of means operated by natural air currents, and including adjustable side and end controlling planes, for automatically maintaining the equilibrium of the aeroplane both crosswise and lengthwise thereof, and independent means, co-operative respectively with such side and 120 end controlling planes, for preventing such automatic adjustment of its controlling planes by air currents exerting less than a predetermined pressure.

8. In an aeroplane, the combination with 125 propelling mechanism, of a framework therefor embodying a plurality of arched frame-pieces disposed crosswise of the machine and in a common plane and also embodying means for fastening said arched 130

frame-pieces together to form a structure substantially rigid crosswise of the machine.

9. In an aeroplane, the combination with propelling mechanism, of a framework therefor embodying a plurality of transverse frames each having a plurality of arched frame-pieces disposed crosswise of the machine and in a common plane and each also having means for fastening said 10 arched frame-pieces together to form a structure substantially rigid crosswise of the machine.

10. In an aeroplane, the combination with a pair of propellers, of a pair of substantially 15 circular propeller frames, a substantially circular motor frame between said propeller frames and in a common plane therewith, and means for connecting said frames to form a structure substantially rigid cross- 20 wise of the machine.

11. In an aeroplane, the combination with a pair of propellers, of a framework embodying means for forming a structure substantially rigid crosswise of the machine, 25 said framework including a pair of substan-

tially circular propeller frames and a substantially circular motor frame.

12. In an aeroplane, the combination with propelling mechanism, of a framework therefor embodying four arched frame- 30 pieces disposed in a common plane and each tangent to every other, and means for fastening said frame-pieces together.

13. In an aeroplane, the combination with propelling mechanism, of a framework 35 therefor embodying four arched frame-pieces disposed in a common plane and each tangent to every other, two of them being substantially circular propeller frames and a third a substantially circular motor frame, 40 and means for fastening said frame members together.

Signed at New York, in the county of New York, and State of New York, this 12th day of March, A. D. 1909.

BERNHARD MONTGOMERY BESKOW.
